UNITED STATES PATENT OFFICE

128,950

DESIGN FOR A CABINET-TYPE EMBALMING APPARATUS

George E. Adams, Catawissa, Pa.

Application May 16, 1941, Serial No. 100,987

Term of patent 14 years

● *To all whom it may concern:*

Be it known that I, George E. Adams, a citizen of the United States, residing at Catawissa, in the county of Columbia and State of Pennsylvania, have invented a new, original, and ornamental Design for a Cabinet-Type Embalming Apparatus, of which the following is a specification, reference being had to the accompanying drawings, forming part thereof.

Figure 1 is a front elevational view of a cabinet-type embalming apparatus showing my new design, with the door of a refuse compartment at one side of the cabinet in open position and the instrument tray at the opposite side of the cabinet in outward position for use.

Figure 2 is a side elevational view thereof from the refuse compartment-equipped side.

Figure 3 is a top plan view thereof.

Figure 4 is a side elevational view thereof from the instrument compartment side.

Figure 5 is a front elevational view thereof similar to Figure 1 but with the door of the refuse compartment closed and the instrument tray in retracted or concealed position, and

Figure 6 is a top plan view thereof similar to Figure 3 and with the door of the refuse compartment closed and the instrument tray in a retracted or concealed position.

I claim:

The ornamental design for a cabinet-type embalming apparatus, as shown.

GEORGE E. ADAMS.
